UNITED STATES PATENT OFFICE.

ANDREW EMERY LISCOMB, OF BAR HARBOR, MAINE.

WOODWORKING-TOOL.

1,083,624.

Specification of Letters Patent. Patented Jan. 6, 1914.

Application filed June 3, 1913. Serial No. 771,429.

To all whom it may concern:

Be it known that I, ANDREW EMERY LISCOMB, a citizen of the United States, residing at Bar Harbor, in the county of Hancock and State of Maine, have invented new and useful Improvements in Woodworking Tools, of which the following is a specification.

This invention relates to improvements in 10 wood working tools and more particularly to a nail-holding attachment for hammers.

The object of this invention is to provide a nail-holding attachment for hammers whereby nails of different sizes may be held 15 and partially driven in position in advance of the usual driving action of the driving face of the hammer.

The advantages of this device are that 20 nails of different sizes may be readily held upon the hammer head, the nail-holding attachment being driven into the handle within, the hammer head acts as a securing means for the handle, and, as it extends above the top of the hammer head, it also 25 acts as an additional fulcrum for the nail drawing claw of the hammer.

While the preferred form of this invention is illustrated upon the accompanying sheet of drawing, yet it is to be understood 30 that minor detail changes may be made without departing from the scope thereof.

Figure 1 is a view in side elevation, with 35 parts broken away, illustrating the application of this invention to a hammer. Fig. 2 is a top plan view of this nail-holding attachment. Fig. 3 is a bottom plan view of this nail-holding attachment. Fig. 4 is a view in perspective of this nail-holding attachment.

40 This attachment comprises a cap 1 adapted to be secured to the top of the hammer head 2 by a depending web 3 being driven into the top of the hammer handle 4. The cap is preferably of the same width as the top 45 of the hammer head and is curved at the rear to extend a slight distance over the top of the claw 5.

The front of the cap is preferably rounded and is provided with a central vertical 50 slot 6, the walls of which extend parallel a short distance inward and then diverge vertically to the vertical transverse rear wall 7, forming a chamber adapted to receive the head of a large size nail, which when the 55 head is so engaged will be supported upon

the upper portion of the driving surface 8 of the hammer. The sides of the cap are preferably vertical and each side is provided with a circular depression 9 having a longitudinal vertical recess 10 extending forward from the inner wall thereof within the body of the cap leaving a portion 11 of the side depending from the top of the recess, which portion is cut away a short distance from the bottom and is curved rearwardly 60 to the top of the circular depression 9 so that the heads of nails of different sizes may be held by inserting the head in the circular depression and then moving the nail bodily forward with the nail head resting upon the 65 top of the hammer head until the shank is engaged by the depending outer wall 11.

The web 3 depends longitudinally and centrally of the cap 1 and is provided at each end with integral transverse wedges 12. 70 The web and wedges not only position the cap but also spread the end of the hammer handle and more firmly secure it to the hammer head.

The top of the cap 1 extends horizontally 75 above the main body thereof and is curved downwardly at the rear to the hammer claw, and, as the cap extends above the hammer head, it also acts as an additional fulcrum for the claw in drawing nails. This attachment, therefore, provides a nail holder, a 80 handle securing wedge, and an additional fulcrum. Of course it is to be understood that this attachment is to be made in different sizes to accommodate it to different size 85 hammers.

What I claim is:—

A nail holding attachment for hammers comprising a cap corresponding in width to the hammer head and means engaging the 90 hammer handle for securing the cap thereon with its under surface contacting with the top of the hammer head, said cap provided on each side with an interior recess extending upward from the under surface and the 95 outer wall of each recess cut away from the bottom and curved upward to the top of the recess, whereby nails of different sizes may be received within the recess and held between the bottom of the side wall and top of 100 the hammer head.

ANDREW EMERY LISCOMB.
